[57] CLAIM

The ornamental design for a sport shoe of the rear fit type, as shown and described.

DESCRIPTION

FIG. 1 is a perspective view of a sport shoe of the rear fit type showing my new design;
FIG. 2 is a side elevational view thereof;
FIG. 3 is a raised front perspective view thereof;
FIG. 4 is a back elevational view thereof;
FIG. 5 is a top plan view thereof;
FIG. 6 is a bottom plan view thereof; and,
FIG. 7 is a side elevational view of the side opposite to that shown in FIG. 2.
